DESIGN FOR A REFRIGERATOR SHOW CASE

William T. Hormes, Catonsville, Md., assignor to
Ottenheimer Bros. Inc., Baltimore, Md., a cor-
poration of Maryland

Application June 15, 1935, Serial No. 57,288

Term of patent 3½ years

To all whom it may concern:

Be it known that I, William T. Hormes, a citizen of the United States, residing at Catonsville, in the county of Baltimore and State of Maryland, have invented a new, original, and ornamental Design for a Refrigerator Show Case, of which the following is a specification, reference being had to the accompanying drawing, forming part thereof.

Referring to the drawing, Figure 1 is a front perspective view of a refrigerator show case illustrating my new design.

Figure 2 is a rear perspective view thereof, on a reduced scale.

I claim:

The ornamental design for a refrigerator show case, as shown and described.

WILLIAM T. HORMES.
